UNITED STATES PATENT OFFICE.

VICTOR E. CLARK, OF GRAND RAPIDS, MICHIGAN.

AIR COMPRESSOR.

Application filed June 15, 1925. Serial No. 37,028.

This invention relates to an air compression mechanism and is designed particularly with reference to mechanism of this character which can be used in conjunction with motor vehicles, the engine of the vehicle being used for the production of compressed air which in turn may be used for the operation of the vehicle. The invention, however, is not restricted in use to motor vehicles and has many other places of use where compressed air at a very high pressure may be desirable or necessary.

A primary object and purpose of the present invention is to compress the air in two stages of compression, one which will produce compressed air at a relatively low pressure and the other take the said air at such lower pressure and compress it to a much higher pressure. Incident to this main object and purpose of the invention are many novel details of construction and arrangements of parts for the effective attainment of the object stated, all of which will appear fully and in detail as understanding of the invention is had from the following description taken in connection with the accompanying drawings, in which,

Fig. 1 is a plan view of the air compression apparatus.

Fig. 2 is a section taken substantially on the broken line 2—2 of Fig. 3.

Fig. 3 is a vertical section through the reversing mechanism forming one part of the construction.

Fig. 4 is an enlarged detail in section illustrative of the worm and screw mechanism for operating the pistons in the second stage air compression apparatus.

Fig. 5 is an enlarged detail in section showing the check valve mechanism interposed between the second stage air compression apparatus and the storage tank for the compressed air.

Fig. 6 is an enlarged detail in horizontal section showing the valve means automatically operative with the periodic reversals of the movements of the pistons so as to direct the air from the primary compressor alternately to the cylinders forming a part of the secondary air compression apparatus.

Fig. 7 is a vertical section of the detail shown in Fig. 6, and

Fig. 8 is a side elevation, with some parts in section, illustrating the assembly of the apparatus.

Like reference characters refer to like

parts in the different figures of the drawings.

The engine, indicated at 1, may be of usual internal combustion type and is adapted to directly drive an air compressor 2 through gears 3 and 4 interposed between the engine and the compressor. The compressed air from the compressor 2 is carried to the rear by a pipe 5 which, at its rear end, is connected with a suitable valve casing 6 from which branch pipes 7 and 8 extend in opposite directions to adjacent the closed ends of two cylinders 9 and 10. Each of said cylinders has an outlet pipe, the respective outlets for the cylinders 9 and 10 being indicated at 11 and 12, leading into a storage tank 13 for compressed air from which the same may be drawn through a pipe 14 to any suitable motor (not shown) adapted to be run by compressed air. This motor in motor vehicles will be associated with the rear axle of the vehicle so as to drive the same. While I have shown a storage tank 13 it is to be understood that this tank may be eliminated and the air to run the motor carried directly through the pipes 11 and 12 from the cylinders 9 and 10 to said air-operated motor.

To the crank shaft of the engine 1 a shaft 15 is connected, the same being continuously driven in one direction when the engine is in motion. This shaft, at its rear end, is equipped with a beveled gear 16 centrally from which a boss 17 projects rearwardly; and the gear at its rear face is also formed with an annular rearwardly extending rib 18 on the inner curved sides of which a plurality of equally spaced apart notches 19 are cut. Directly back of the gear 16 is a second beveled gear 20, the beveled faces of gears 16 and 20 being adjacent each other. From this gear 20 a shaft 21 extends to the rear. Gear 20 on its front face is formed with a forwardly extending sleeve 22, into which the boss 17 extends. Between the gears a ring 23 of metal is located formed in its forward face with an annular groove 24 into which the annular rib 18 of gear 16 extends, this groove being around a central annular sleeve portion 23^a of the ring 23, as shown in Fig. 2. The ring 23 at a plurality of points equally spaced apart has transverse slots or openings cut through the same from front to rear through which beveled pinions 25 mounted on pins 26 may pass. These pinions mesh with both gears 16 and 20. Between the pinions 25 pins 27 are

mounted, extending radially through the ring and at their inner ends being formed with forwardly turned fingers 28 which are normally adapted to seat in the recesses 19 heretofore described, being moved toward said recesses between coiled springs 29, as shown, and locking gear 17 and said ring together.

A band 30 of flat metal surrounds the ring 23 and at equally spaced apart points has sections 31 pressed outwardly each at one end terminating in an out-turned lug 32. There are four of these sections 31, one for each of the pins 27, and said sections 31 are pressed outwardly from the band and progressively extend farther away from the band until they terminate in the lugs 32 described. At diametrically opposed points in the ring 23 two pins 33 are secured, the same extending through slots 34 in the band 30. Coiled springs 35 are attached at one end to the pins 33 and at their opposite ends to the bands 30, the tendency of these springs being to move the band with reference to the ring so that the pins 27 may freely project outward until the fingers 28 seat in the notches 19.

On a stationary vertical support 36 located in front of and adjacent the gear 16, a bar 37 is pivotally mounted on a pivot 39 having an end section 38 turned substantially at right angles so as to extend over the band 30. The opposite end is turned downwardly as indicated at 40 parallel to the support 36 which carries a leaf spring 41 bearing against the part 40, the tendency of which is to turn the section 38 downwardly into the path of movement of the projecting lugs 32.

The gears 16 and 20 and the elements associated therewith described are located in front of the cylinders 9 and 10 which are spaced apart from each other and between which a supporting casting 42 is disposed from which two spaced apart ears 43 extend upwardly. Between the ears 43 a worm or tangent wheel 44 are located, it being rotatably mounted in said ears. The shaft 21 carries a worm 45 meshing with the worm wheel 44 and is continued to the rear edge of the casting 42, having rotatable mounting in the upper end of a post 46 extending upwardly from and integral with said support.

The worm wheel 44 is centrally bored and interiorly threaded. Two pistons 47 are located in the cylinders 9 and 10 and a rod 48 connects the pistons, the intermediate portion of which is threaded as indicated at 49 and passes through the worm wheel 44. It is evident that with the rotation of the shaft 21 pistons 47 are moved one toward the closed end of its cylinder and the other away from said closed end and the location of the pistons in the cylinders is such that when one piston is near or approaching the closed

end of its cylinder the opposite piston is near or approaching the open end of its cylinder.

A trip bar 50 is fixed to the rod 48 at one side of the ears 43 being adapted to rock or trip a rock bar 51 formed with in-turned ends 52 and pivotally mounted at 53 on the support 42. That is, (referring to Fig. 1) with the piston 47 in cylinder 9 moving to the left, the trip bar 50 will engage with one of the fingers 52 of the bar 51 and will rock the bar about its pivot 53 and on the return stroke of the pistons, as will later be described, when the trip bar reaches the opposite finger 52 it will rock the bar 51 back to its original position. The bar 51 is formed at the end of a lever 54 which extends to and alongside of the depending portion 40 turned downwardly from the lever 37, at its front end being formed with a slot 55 therein best shown in Fig. 1.

Within the valve casing 6 a valve 56 is mounted at its upper end carrying an arm 57 at the free end of which a pin 58 extends upwardly and passes into and through the slots 55. The valve 56 has a passage therethrough such that when turned to one position, as shown in Fig. 6, air from the pipe 5 is directed through the pipe 8 to the cylinder 10 and when turned substantially a quarter turn to another position the air will be directed through the pipe 7 to the piston 9.

With the engine operating and with the parts in the position shown in Fig. 1, that is with the lever 54 bearing against the part 40 so as to elevate the section 38 above the outwardly extending lugs 32, the air from the compressor 2 is directed into the cylinder 10. The shaft 15 is driven continuously and the entire mechanism, including the gears 16 and 20 and the parts associated therewith, turned in one direction indicated by the arrow in Fig. 3, thereby turning the shaft 21 in the same direction as the shaft 15. This moves the piston 47 in the cylinder 9 toward the closed end of the cylinder and compresses the air in such cylinder forcing it into the storage tank 13 or, if such tank is omitted, forcing it directly to the air motor driven by the compressed air. In the pipes 11 and 12 or between said pipes and the cylinders 9 and 10 a valve casing 59 is located (see Fig. 5) in which a check valve 60 is mounted having a rod 61 extending therefrom around which is a spring 62 normally serving to hold the valve in closed position in addition to the pressure of the air in the tank 13, but when the pressure in the cylinder 9 gets above that in the storage tank 13 the valve is unseated and the air forced into said storage tank. The movement of the piston 47 in the cylinder 9 toward the closed end of the cylinder continues until the trip bar 50 rocks the bar 51 whereupon the lever 54 is moved away

from the depending part 40 and the spring 41 moves the section 38 downwardly into the path of movement of the outwardly extending ears or lugs 32 of the band 30. When this occurs the band is stopped and slips over the ring 23, springs 35 stretching, and the pins 27 are forced inwardly until they disengage from the notches 19, thus breaking the connecting engagement between the gear 16 and the ring 23, whereupon band 30 and the ring 23 remain stationary. The gear 16 continues to move in its same direction of movement but drives the gear 20 in the opposite direction through the interposed pinions 25. This effects a reversal of the movement of the pistons 47 and it is evident that with the rocking of the bar 51 the valve 56 has been turned to another position so as to change the passage of the compressed air from the cylinder 10 to the cylinder 9. The air which has been compressed in compressor 2 and carried into the cylinder 10 is then further compressed by the movement of the piston 47 toward the closed end of the cylinder. At the same time the compressed air from the compressor 2 is carried into the cylinder 9 during the time that the piston 47 is moving toward the open end of the piston. This continues until on the return movement of the trip bar 50 it engages the opposite finger 52 and rocks the bar 54 back to position where it engages against the depending portion 40 of the lever 37 and disengages the end 38 thereof from the lug 32 with which it has been disengaged, whereupon shaft 21 again moves in unison with the shaft 15 and not in a direction opposite thereto.

From this construction it will be apparent that the air from the compressor 21 is alternately carried to the cylinders 9 and 10 and further compressed therein to a higher degree of pressure. In this manner the air may be compressed to a very high pressure, it being apparent that the worm gear connection between the pistons 47 and the engine driving the same permits an exceedingly high pressure of air to be obtained.

The construction described when used in connection with any motor adapted to be driven by compressed air is very effective and with motor vehicles it is evident that the usual clutch, gear shift and transmission may be entirely omitted, the air motor being driven at any desired speed in accordance with the amount of compressed air supplied thereto. The two stage compression of the air is particularly effective. As before stated the storage tank 13 may be eliminated and the air taken directly from the secondary compressors to the air operated motor, obviating any of the difficulties of holding air at a very high pressure in a storage tank which might be liable to leakage. Many changes in the detail of construction may be

resorted to without departing from the invention which is defined in the appended claims and which is to be considered comprehensive of all forms of structure coming within the scope of said claims.

I claim:

1. In combination, an engine, an air compressor driven by the engine, two cylinders, means for alternately delivering compressed air from the compressor to said cylinders, and means directly driven by the engine operating in said cylinders to further compress the air therein, said means compressing the air in one cylinder while compressed air from the compressor is being delivered to the other cylinder.

2. In combination with an engine, an air compressor driven thereby, two cylinders oppositely located with respect to each other, pistons in the cylinders, a rod connecting the pistons, a pipe leading from the air compressor, branch pipes leading from said cylinders to said first pipe, valve means between said first pipe and the branch pipes operable to direct the compressed air to either cylinder, means for moving said pistons and the rod connecting the same back and forth driven by said engine, and means for automatically turning said valve in conjunction with the movement of said pistons whereby on movement of the pistons to compress air in one cylinder air from the compressor is delivered to the opposite cylinder.

3. In combination with an engine, an air compressor driven by the engine, a pipe leading from the air compressor, a valve casing to which said pipe is connected, a valve in the valve casing, two branch pipes leading from the valve casing, two cylinders having each a closed end to which said pipes are connected adjacent said closed ends, pistons in the cylinders, a rod connecting the pistons, means driven by the engine for moving said pistons in the cylinder, trip means secured to said rod and connected with the valve for automatically turning the valve to change the direction of flow of compressed air on predetermined movement of said rod in either direction, and means disposed between the engine and said rod operating means for automatically reversing the movement of said operating means when said trip means is actuated.

4. In combination with an engine, an air compressor driven by the engine, two cylinders each having one end closed located in spaced apart relation with their open ends toward each other, two pistons in said cylinders, a rod connecting the pistons, said rod having its intermediate portion threaded, a worm wheel having an internally threaded opening therethrough through which the threaded portion of the rod passes, a shaft, a worm thereon engaging with the worm wheel, connections between the compressor

- and the cylinders adjacent their closed ends for carrying compressed air from the compressor to the cylinders, valve means in said connections for alternately directing the compressed air to said cylinders, means for automatically operating said valve means on movements of the rod connecting the pistons to predetermined points in either direction, and means interposed between the engine and said worm carrying the shaft for driving said shaft in opposite directions combined with means for reversing the direction of movement of said shaft upon operation of the trip means, substantially as described.
5. In combination with an engine, a compressor driven by said engine, two cylinders each having a closed end, pipe connections between said compressor and cylinders, a valve in said connection adapted to be operated to two different positions, whereby compressed air is directed to either one or the other of said cylinders, means in said cylinders operated by the engine for further compressing the compressed air delivered to 20 either cylinder, and means for automatically turning said valve when one cylinder is sub-
- 10 15 20 25

stantially filled with compressed air to thereby direct the compressed air to the opposite cylinder and simultaneously operate said compressing means in the cylinders to further compress the air in the filled cylinder and operate the compressing means in the opposite cylinder outwardly to provide space therein for the reception of the air from the compressor.

6. In mechanism of the character described, an air compressor, means for driving the same, two receptacles, means for alternately delivering compressed air from the compressor to said receptacles, and means for alternately further compressing the air in said receptacles driven by said air compressor operated means, a storage tank connected with said receptacles and conduits leading from the receptacles to the storage tank for carrying the further compressed air from the receptacles to said tank combined with check valves in said conduits stopping return movement of air from said storage tank to said receptacles.

In testimony whereof I affix my signature.
VICTOR E. CLARK.
